UNITED STATES PATENT OFFICE

141,784

DESIGN FOR A DICKEY

Sara Mirsky, New York, N. Y.

Application March 7, 1945, Serial No. 118,316

Term of patent 3½ years

(Cl. D3—25)

To all whom it may concern:

Be it known that I, Sara Mirsky, a citizen of the United States, residing in the city of New York, county of New York, and State of New York, have invented a new, original, and ornamental Design for a Dickey, of which the following is a specification, reference being had to the accompanying drawings, forming a part thereof.

In the drawings:

This application is a continuation-in-part of the application Ser. No. D-113,797, filed May 29, 1944, for a dickey.

I claim:

The ornamental design for a dickey, as shown.

SARA MIRSKY.
